SUPPORTING DEVICE

Filed Sept. 28, 1928

FIG. 1

FIG. 2

FIG. 3

Inventor
NATHAN H. FOX

BY: *Ben V. Zillman*
Attorney

UNITED STATES PATENT OFFICE

NATHAN H. FOX, OF ST. LOUIS, MISSOURI

SUPPORTING DEVICE

Application filed September 28, 1928. Serial No. 308,907.

My invention relates to improvements in a supporting device, and more particularly to a device of the kind described, which shall be simple, safe and reliable in action, easy to use, sturdy, and efficient and satisfactory for use wherever found applicable.

In certain kinds of structural work, as for example, in plastering, acoustical work, etc., it is necessary that the worker stand upon a scaffold or the like, and perform the various details of his craft upon some object overhead. The scaffold upon which he stands is rather flimsy in construction so that the tread thereof will "give" or "spring" somewhat as he walks from place to place on the scaffold, due to the fact that the points of support for the scaffold are spaced relatively great distances apart and also to the fact that the boards constituting the tread are thin so that they may be easily handled in placing them upon and taking them off the scaffold supports.

One of the objects of my invention is to provide a work-support particularly adaptable to be placed upon such scaffolds, extending thereabove and engageable with a piece of work positioned thereabove, and which will "give" with the flexing of the scaffold itself, all without releasing its support of the particular piece of work with which it is in contact.

Another object of my invention is to provide a resilient support of the kind described, which may be adjusted to take care of the variations in thickness of the piece of work, or for other reasons.

Many other objects and advantages of the construction herein shown and described, will be obvious to those skilled in the art to which this invention appertains, from the disclosures herein given.

To this end, my invention consists in the novel construction, arrangement and combination of parts herein shown and described and uses mentioned and more particularly pointed out in the claim.

In the drawings, wherein like reference characters indicate like or corresponding parts throughout the views,

Figure 1 is a side elevation of my device, 50 mounted in operative position;

Figure 2 is a detail of the same, partly in elevation and partly in section; and

Figure 3 is a plan view of the housing itself, as viewed from the bottom end.

Referring more particularly to the drawings, wherein I have illustrated the preferred embodiment of my invention, 1 indicates the ceiling or overhead wall upon which certain work is to be done from below. In plastering, particularly with certain classes of buildings, a great deal of ornamental work is placed upon the ceiling, these ornaments being generally pre-cast at some point distant from the building being erected, one of such ornaments being indicated at 2. Such ornaments are held to the wall thereabove by the plaster itself, and as it has considerable weight, it must be held in place until the plaster is sufficiently hard or set, to hold it without support from below. As these pieces are brittle, no nails or similar fastening means may be used for the temporary support thereof while the plaster is setting.

The scaffold supports 3 may be either as shown, or supported from above, or otherwise, as the case may be or as the need arises, and upon these spaced supports the tread 4 is formed of boards, in the usual manner. The boards forming the tread are generally about an inch or so in thickness so as to enable them to be handled without too great difficulty, and as a consequence of this, and of the fairly great distances between the adjacent supports 3, the boards will "give" or flex as the workman moves thereacross, as indicated in the dotted lines in Fig. 1.

The supporting device proper, comprises a work-engaging element 5, a scaffold-engaging element 6, and means therebetween to resiliently interconnect the same and permit a certain amount of relative longitudinal movement therebetween.

A housing member 7 is made, somewhat as shown, cheaply and sturdily, through which the scaffold-engaging member 6 may pass longitudinally, the opening through the housing being sufficiently greater than the parts passing therethrough, so as to permit pieces of plaster and the like to fall freely there-

through from thereabove, without clogging up the same.

A spirally coiled spring 8 encircles the rod 6, forming a loose sleeve therefor, one end of the spring being secured to the rod between a pair of nuts 9 shown at the innermost end of the rod. The other end of the spring is fixed to the housing, adjacent the lower end of the latter, as by looping said end of the spring about a bolt 10 positioned diagonally through the adjoining sides of the housing. Obviously, the rod may be moved longitudinally of the housing, inwardly or outwardly, and without danger of the parts becoming displaced or lost.

The work-engaging element 5 may be of a suitable length of board, having securement to the housing in some suitable manner, preferably so that a certain amount of longitudinal adjustment therebetween may be had, as for example by providing a series of apertures 11 through the part 5, through which a pair of bolts 12 may be passed from within the housing, wing-nuts 13 maintaining the parts in their adjusted relationship.

The device just described is extremely sturdy, economical, easy to set up and take down, occupying but little space in storage or in place, and will remain in its desired position as long as necessary, without paying further attention thereto after it is once set up, the spring automatically taking up any vibration of the scaffold that may occur. There is no danger of the scaffold-engaging rod slipping out of place, as it is rather small in diameter, say about an inch or so, and will therefore bite into the scaffold itself and thereby keep its engagement therewith.

Any number of these supports may be used in case the single one is not sufficient, the devices being placed at suitable points so that they engage the work at a plurality of points.

Having thus described my invention, it is obvious that various immaterial modifications may be had in the same without departing from the spirit of my invention; hence I do not wish to be understood as limiting myself to the exact form, construction, arrangement and combination of parts herein shown and described, or uses mentioned, except as limited by the claim.

What I claim as new and desire to secure by Letters Patent is:

A work-holding support of the kind described, adapted to support a piece of work overhead and comprising a housing member, a scaffold-engaging member telescoping with said housing member, a coil spring encircling and receiving said scaffold-engaging member therethrough and fixed at one end to the same and fixed at its other end to the other member to resiliently control relative movement therebetween, substantially as described.

NATHAN H. FOX.
